UNITED STATES PATENT OFFICE.

FRANK WILCOMB, OF NORRISTOWN, PENNSYLVANIA, ASSIGNOR TO WILDMAN MFG. CO., OF NORRISTOWN, PENNSYLVANIA, A CORPORATION OF PENNSYLVANIA.

INTERLOCKING SINKER AND WEB-HOLDER.

1,255,258.

Specification of Letters Patent.

Patented Feb. 5, 1918.

Application filed August 14, 1916, Serial No. 114,804. Renewed July 11, 1917. Serial No. 180,018.

To all whom it may concern:

Be it known that I, FRANK WILCOMB, a citizen of the United States, and a resident of Norristown, Pennsylvania, have invented 5 certain new and useful Improvements in Interlocking Sinkers and Web-Holders, of which the following is a specification.

The invention relates to knitting machines of the type employing sinkers and web-holders. The main feature of the invention 10 consists in a combined sinker and web-holder in which, while separate elements or units are employed, one constituting the sinker and the other constituting the web-holder, these two elements are operable in 15 one bed, or in one slot, one of said elements effecting the operation of the other of said elements, as will be hereinafter described and particularly pointed out in the claims.

20 The invention is shown in the accompanying drawings in which—

Figure 1 shows a transverse sectional view of part of a needle carrier and a sinker and web-holder bed, with the sinkers and web-holder combination in position to supply 25 yarn to the needle.

Fig. 2 is a view like Fig. 1, but with the sinkers advanced and the web-holder also in advanced position.

30 Fig. 3 is a similar view showing the parts in the position as assumed by them during the pressing action.

Fig. 4 shows a different position of the parts, the sinker having shed the new loop 35 and these new loops being in the act of evening across the tops of the web-holders.

Fig. 5 shows the position of the parts similar to Fig. 1, excepting that here the needle has drawn its loop into the fabric.

40 Fig. 6 shows the sinker and web-holder slightly advanced from the position as in Fig. 5, and that the needle is about to rise, while the fabric is held down by the web holder.

45 Fig. 7 shows a different relation of presser wheel.

Figs. 7^a and 7^b illustrate details of Fig. 7.

Fig. 7^c shows views of one form of web holder detached.

50 Fig. 8 illustrates a combination of pivotally mounted sinkers and the form and arrangement of web holders to coöperate therewith.

Fig. 9 illustrates certain parts of the beds 55 to receive the knitting elements, needles, web holders and sinkers.

Figs. 10 to 13 illustrate details.

Fig. 14 is a view of a web holder.

Fig. 15 shows views of a sinker.

In these drawings, 1 indicates a needle carrier which may be a cylinder of ordinary form, or any other kind of needle carrier may be employed. This needle carrier has grooves, as in ordinary practice, for the guidance of the needle. 2 indicates a web holder 60 of substantially ordinary form, so far as its upper and lower surfaces and its nose are concerned, and 3 indicates a sinker having a nose of substantially ordinary form. Both the web holder and the sinker are mounted 65 in the same bed, and each web holder is mounted in the same slot of the said bed, with its companion sinker. The sinker is operated by a suitable cam, engaging its butt 4, said cam being represented in section at 5, this cam being mounted on the under side of a suitable cap plate. The sinker at its outer end, which carries the butt, is in a lower plane than the inner end where the nose is located; and the said 70 outer portion of the sinker has full guiding connection, or engagement, with the slot in which the sinker slides. The inner portion of the sinker, where it engages the outer end of the web holder, has shoulders at 6 and 7. 75 These shoulders are located at a greater distance apart than the width of the tail, or outer portion, 8 of the web holder, so that movement of one element can take place to a certain extent in relation to the other element as hereinafter indicated. The web 80 holder is under pressure of a spring band 9, which is located in notches 10 of the respective web holders, and this spring tends constantly to force the web holders inwardly 90 toward the needles, into position to perform their web holding functions. When the sinkers are retracted, however, to the position shown in Fig. 1, the shoulder at 7 on the sinker will engage the upstanding tail 100 portion of the web holder, and will retract the same to the position indicated in said Fig. 1, it being understood that the sinker 105 is operated solely by its cam. In the position of the parts shown in Fig. 1, the sinker and web holder are retracted to their extreme limit to allow the yarn to be presented to the sinker in front of the nose thereof, and as just stated, this extreme retracted position of the web holder unit is 110 due to the action of the sinker in engaging it and retracting it positively against the

tension of the spring band 9. When the sinker is advanced to sink the loops between the needles thereof, the spring 9 causes the web holder to follow up the advancing movement of the sinker until the nose of the web holder comes against the fabric, and then the shoulder 6 of the sinker comes against the tail portion of the web holder and holds it in this advanced position, Fig. 2, or causes it to advance a short distance farther, in case of a web holder not advancing freely under the influence of the spring band. This view also illustrates a presser device outside the needle row at 11, and forming part of the wall of the sinker bed. This presser is in such position that as a needle passes upward, or downward, it is pressed by this wall provided the needle is forced outwardly by a presser wheel or other presser device inside the needle row, and indicated at 12 in Fig. 3.

In Fig. 2 both the sinker and web holders are fully advanced, but in Fig. 3, which represents the position of the parts during the pressing of the needle beard the sinker is slightly retracted to relieve the yarn from excessive strain across the stem of the needle, and the web holder is in its advanced position holding the fabric loops in definite position to aid the needle beards in passing through them, as they are pressed. This view shows that the needle beard is pressed at a point between the new yarn and the old fabric loop preparatory to the further downward movement of the needle.

Fig. 4 shows the sinker retracted to shed the new loop and in its retracting movement the sinker has withdrawn the web holder slightly to permit the needle beard to pass through the fabric loop without bursting it and furthermore, the web holder is in position to allow of evening of the loops across the tops of the web holder nibs.

Fig. 5 shows the sinker still further retracted and the web holder is also retracted and has shed its evened loop which now has been drawn into the fabric.

Fig. 6 shows the sinker slightly advanced from the position of Fig. 5 permitting the web holder to advance and seize the fabric to prevent it from rising when the needle rises to receive the new yarn, the elevated position of the needle at this time being indicated by dotted lines.

The above described series of steps and movements may now be repeated, starting with Fig. 1, which in respect to Fig. 6 just described, shows the sinker and web holder retracted to an extreme position, and while this is not the necessary movement over that in Fig. 6, it provides for a thread carrier, or thread delivery eye, positioned in front of the sinker instead of above it, which would be required if the extreme outward limit of movement was that indicated in Fig. 6.

The mode of sinking the yarn, pressing the needle beards, and evening the loops prior to drawing them into the fabric, and drawing the stitches into the fabric, does not differ materially in the use of this double implement with its units in the one groove, over the usual form, of sinker and web holder arrangement, in which two separate instruments are employed, supported in independent beds or carriers and independently operated, and it is not the purpose of this invention to depart from the accepted mode of handling the yarn and the formation of the stitches. I have provided, however, a simpler construction and mounting of the parts, and a mode of handling the yarn which differs materially from direct-fed needle machines, which employ no sinkers, and from a "double-nosed sinker" which is a one-piece implement having a sinker notch and a web holder throat, in which the sinking action and web holding action are necessarily performed simultaneously, whereas the operations should be distinct from one another. With the "double-nosed" sinker arrangement just mentioned, evening the loops prior to drawing them into the fabric cannot be done.

This evening action is recognized by those skilled in the art, as a desirable, if not an essential step in the successful performance of sinker knitting. The only evening action possible to obtain with a "double-nosed" one-piece implement is one that takes place after the new loops are drawn through the old loops, but this does not accomplish the object aimed at, such as can be done by evening the loops prior to drawing them into the fabric.

The foregoing description of the implement, so far as sinking the yarn, pressing the needle beard, evening the new loops, and knocking the loops over the needles are concerned, do not differ in substance from that shown in my Patent No. 1,072,302, September 16, 1913. It will be seen from the above, however, that I have provided a compound implement requiring only one needle bed and one needle slot for each pair of units constituting the compound implement; that the units of each pair are interlocked for certain movements in common, but that all the movements are controlled, either directly or indirectly, from a single cam set acting upon one of the units.

The invention is not limited in its use to spring beard needles.

Referring to Fig. 7 this shows a slightly different arrangement and proportion of the web holders and sinkers adapted to receive the presser wheel between them, instead as in the form first illustrated of having the presser wheel operate in a plane above the sinkers. It will be understood that with the arrangement of Fig. 7 all the movements above described are carried out as stated. 130

Fig. 7^a illustrates in detail a form of presser ring outside the needle row against which the beard is pressed when the needle is deflected outwardly by the presser wheel.

5 This presser ring 11^x is slotted on its under side to guide the web holders and on its upper side to guide the sinkers. The web holders are also guided by their lower portions moving in slots at the inner edge of 10 the sinker bed, as shown in Fig. 7^b, the sinkers also being guided in the outer portion of this slotted bed.

As illustrating the fact that my invention is not limited, and the claims are not intended 15 to be interpreted as limited, to the particular organization shown in Figs. 1 to 6 I show in Fig. 8 an organization in which the web holders and sinkers are pivotally mounted. The parts in this figure correspond 20 substantially in function to those before described in so far as they are designated by reference characters are indicated by characters corresponding to those used hereinbefore with the addition of the exponent "a."

The web holders travel in an arc shaped path on the top of the bed 14, which is not milled at this upper surface, but is a turned or machined surface, thus contributing not 30 only to ease of manufacture but also to accuracy. The web holders are guided between presser elements 15 held by this bed, which is slotted at 16 across its top and vertically upon its outer side or face at 17. The 35 presser elements consist of pieces 15 shown in detail in Figs. 11, 12 and 13 and Fig. 10 is a plan view showing the upper face of the presser bed or ring 14, the parts or surfaces 18 between the slots being the bearing surfaces 40 upon which the lower edges of the web holders rest and slide. The presser elements are of general inverted U-shape having two depending prongs as shown in Fig. 13, the inner prong 15' fitting down against the 45 inner face of the bed 14 while the other prong 15'' fits in the outer slot 17 of the bed. The presser elements are removable and are preferably held in place by spring rings 19 though these may be held by friction or in 50 other ways. Any one of the presser elements may be removed for renewal or repair by simply pulling it up from engagement by the spring band. The sinkers 3^a have their upper arc shaped portions guided between 55 the upper portions of the presser elements and depending lugs 3^x of the sinkers which operate between the shoulder of the web holders lie and work between these upper ends of the presser elements. The sinkers 60 are also guided by slots in the underside of the cap plate 20 forming a part of the inclosing casing and this cap serves to hold the sinkers in their pivot seats 21. The presser elements are slightly rounded at their 65 upper inner corners to receive the needle

beards and the inner faces of these elements may be grooved, as shown at 15^x.

The presser units may be formed of hardened steel. The noses of the web holders which are thinned are guided in slots of the 70 web ring 22. The cam for operating the sinkers is shown at 23. The sinkers have arms which are guided in the slots 24 of a cage 25. The presser elements in one aspect form a part of the bed 14 and serve to guide 75 both the web holders and the sinkers, being like Fig. 1 and Fig. 7 in this respect, wherein in the two elements, sinkers and web holders, are guided in the same bed.

Features relating to the outside presser 80 made up of removable elements not claimed herein will be claimed in another application for Letters Patent of the United States, 114,805, filed August 14, 1916.

What I claim is:—

85

1. In combination, a needle carrier, needles, a series of individual sinkers and a series of individual web holders, and means for operating one of said series which in turn operates the other series, substantially as 90 described.

2. In combination a needle carrier, needles, individual sinkers and individual web holders, and cam means for operating the sinkers, said sinkers operating the web holders, substantially as described.

95

3. In combination a needle carrier, needles, sinkers, web holders detachably engaged by the sinkers and means for operating the sinkers, which in turn operate the web holders, substantially as described.

100

4. In combination, a needle carrier, needles, a set of sinkers, a set of web holders, means for operating the sinkers which in turn impart to the web holders some of the necessary movement and means for giving other movement to said web holders, substantially as described.

105

5. In combination a needle carrier, needles, a set of sinkers, a set of web holders, a bed having grooves with a sinker and web holder in each groove of said bed, a cam for operating the sinkers, which in turn operate the web holders and a spring for additionally operating said web holders, substantially as described.

110

6. In combination a needle carrier, needles, a set of web holders, spring means for operating the web holders toward the needles and cam operated sinkers for operating the web holders in opposition to the spring means, substantially as described.

115

7. In combination, a needle carrier, needles, a set of web holders, a set of sinkers, means for operating the sinkers, said sets having a lost motion connection, through which the operated sinkers actuate the web holders, substantially as described.

120

8. In combination, a needle carrier, needles, a set of web holders, a set of sinkers,

125

130

- means for operating the sinkers, said sets having a lost motion connection, through which the operated sinkers actuate the web holders, and means for additionally operating the web holders, substantially as described.
9. In combination in a knitting machine, sinkers and web holders interlocked and means for operating the sinkers which operate the web holders, said parts in addition to their movement in common having relative movement.
10. In combination, in a knitting machine, a needle carrier, sinkers and web holders having shoulders by which they are interlocked, whereby one will move the other, and operating means, substantially as described.
11. In combination in a knitting machine, a needle carrier, web holders, sinkers overlying the web holders in part and having low portions guided in rear of the web holders, and means for operating the sinkers, which in turn operate the web holders, substantially as described.
12. In combination, a needle carrier, web holders, sinkers overlying the web holders and having spaced apart shoulders for engaging the same, cam means for operating the sinkers, which in turn operate the web holders, and spring means engaging the web holders for additionally operating them, substantially as described.
13. In combination, a needle carrier, needles, web holders therefor, sinkers having spaced apart shoulders and embracing the tail of the web holders to operate them with lost motion, said sinkers having low portions with means for guiding the same, and a spring band engaging the tail of the web holders for additionally operating them, substantially as described.
14. In combination, pivotally mounted sinkers, means for operating them, and individual web holders operated by the sinkers, substantially as described.
15. In combination, slidable web holders, and pivoted sinkers operating the web holders and means for operating the sinkers.
16. In combination movable web holders, and sinkers reaching over the web holders and pivotally mounted below the plane of the web holders, said sinkers operating the web holders and means for operating the sinkers, substantially as described.
17. In combination, individual web holders, pivoted sinkers operating the web holders and having arms extending outwardly from their pivots with cam means operating the said arms.
18. In combination, individual web hold-
- ers, movable in an arc shaped path, and pivoted sinkers engaging and operating the web holders, with means for operating the sinkers, substantially as described.
19. In combination, individual web holders, movable in an arc shaped path, and pivoted sinkers engaging and operating the web holders, with means for operating the sinkers, and a bed having a curved machined surface on which the web holders move, substantially as described.
20. In combination, slidable web holders, a bed therefor, sinkers pivoted to said bed below the plane of the web holders and reaching over the web holders and interlocking therewith to operate the web holders, and means for operating the sinkers, substantially as described.
21. In combination individual web holders, pivoted sinkers interlocking with the web holders for operating the same, means for operating the sinkers, and a bed in which both the sinkers and web holders are guided.
22. In combination individual web holders, pivoted sinkers interlocking therewith for operating them, a bed in which the web holders and sinkers are guided, and a cap plate engaging the sinkers and slotted to guide them, and means for operating the sinkers.
23. In combination in a knitting machine, web holders, sinkers separate from the web holders, a bed having guide grooves common to both the web holders and sinkers, and cam means for operating the sinkers, said sinkers operating the web holders, substantially as described.
24. In combination in a knitting machine, individual web holders, sinkers, means for operating the sinkers which in turn operate the web holders, additional means for operating the web holders, said web holders in connection with the needles evening the loops across their tops, substantially as described.
25. In combination, a bed, pressing elements held by said bed, a presser device to deflect the needles outwardly against said presser elements, web holders guided between the presser elements, and on top of the bed, sinkers closely overlying the web holders, and means engaging the upper surfaces of the sinkers to hold them down to work upon the web holders and means for operating the sinkers, which in turn operate the web holders, substantially as described.

In testimony whereof, I affix my signature.

FRANK WILCOMB.
